UNITED STATES PATENT OFFICE.

EARL K. HOLMES, OF CLEVELAND, OHIO, ASSIGNOR, BY MESNE ASSIGNMENTS, TO STEEL AND TUBES, INC., OF CLEVELAND, OHIO, A CORPORATION OF OHIO.

POLISHING MACHINE.

Application filed May 12, 1926. Serial No. 108,455.

This invention relates to polishing machines, particularly those adapted for polishing rods and tubes and similar elongated articles.

5 An object of the invention is to produce a polishing machine which will be rapid and efficient in operation.

Another object is to provide a polishing machine which will be compact and occupy 10 little floor space.

Another object is to provide a polishing machine at which two operators may work simultaneously and which may be controlled by either operator.

15 Another object is to provide a polishing machine in which a plurality of articles may be simultaneously polished.

Other objects will hereinafter appear.

The invention will be better understood 20 from a description of one practical embodiment thereof illustrated in the accompanying drawings, in which—

Fig. 1 is a front elevation of a machine constructed to polish round bars or tubes.

25 Fig. 2 is a side elevation of the machine illustrated in Fig. 1.

The machine illustrated comprises a base 1 carrying at its top a flat bed 2, having ways 3 in which bearing supports 4 may 30 slide transversely of the machine. The supports may be easily and quickly adjusted transversely of the machine by screws and hand wheels 5 and are normally adjusted to maintain a considerable tension on the 35 polishing belts.

In the bearings at the top of these supports are mounted parallel shafts 6. At each 40 end of each shaft a pulley 7 is positioned and the intermediate part of one of the shafts carries a drive pulley 8.

Belts 9 run around the pulleys 7 on corresponding ends of the shaft. On each end of the base, below and intermediate the shafts, is positioned a carrier 10, mounted to reciprocate vertically and operated by a rod 11 45 carried in bearings 12 through which it is free to slide. The upper ends of the carriers are provided with openings through which the bars or tubes may be slid. In the machine illustrated there are three such openings in each carrier, two small at 13 and one large at 14 for receiving different sizes of pipe.

The lower end of each vertically moving 50 rod 11 is connected by a link 15 to a pedal

lever 16 pivoted to the lower part of the standard. The levers 16, 16 are connected positively so that they must be moved up or down together. A convenient way of doing this is as illustrated by extending the levers 60 beyond their respective pivots and connecting the ends together by a link 17 as shown. The carriers are depressed by pressure on the pedals and are elevated upon release of the pedals by springs 18. By so arranging 65 the pedals that both carriers are controlled by either operator, all danger of injury to the belts due to pipe being inserted in either carrier is eliminated. Upon depression of either one of the pedal levers 16 both carriers 10 are depressed so that pipe inserted into either carrier may be passed on through and inserted through the opposite carrier without danger of its end engaging the side edge of the belt and tearing, cutting or otherwise injuring the belts. By this arrangement two operators may polish pipe simultaneously on one machine. Either operator may depress one of the pedal levers 16 which depresses both carriers 10, then both operators 70 may insert a pipe between his respective carrier and the belt thereabove and also push his pipe between the opposite carrier and the belt thereabove without danger of injury to either belt. When pressure upon the pedal 75 levers is released the carriers move upwardly to bring the pipe into engagement with the moving belts.

The mounting of the pulley shafts close together permits the use of short and relatively inexpensive belts as well as making the machine compact. Moreover, there is comparatively little sag in the unsupported part of the belt, due to its short span, so that the tension of the belt may be relied on to provide 80 pressure enough for polishing.

The operation of the device is as follows:

The operator steps on one pedal, which depresses both carriers and then inserts a pipe in corresponding notches 13 or 14 in 100 each carrier so that its surface will be polished by the moving belts. After inserting the pipes the operator releases the pedal and the springs press the pipes against the polishing belts. As the belts move and polish 105 the surface, the operator feeds the pipe through the machine. Simultaneously with this operation, an operator standing on the other side of the machine may be likewise polishing and feeding a pipe through another 110

pair of notches in the carriers. When the pipes have been fed through the machine so far that the end which each operator holds to direct and feed the pipe becomes too short for convenience, the operators may exchange pipes and each then pulls the pipe received through the machine towards him, finishing the polishing operation.

The carrier may be provided with differently sized openings as shown at 13 and 14, so that the machine may be used for different sizes of pipe, without change of parts.

I claim—

A polishing machine comprising two tensioned polishing belts passing around pairs of pulleys, the portions of the belts between

the pulleys being unsupported and parallel and extending substantially horizontally, a pair of cradles for supporting a piece of work to be pressed against the belt, the 20 cradles being positioned intermediate the pulleys and below the belt and vertically movable, springs attached to said cradles moving the same together with the work supported thereby upward, and a pair of pedals 25 connected together by linkage, either pedal simultaneously moving said cradles downwardly, one pedal being accessible from each side of the machine.

In testimony whereof I hereunto affix my 30 signature this 4th day of May, 1926.

EARL K. HOLMES.
